UNITED STATES PATENT OFFICE.

WALTER E. DUNCANSON, OF NEW YORK, N. Y., ASSIGNOR TO THE J. G. WILSON CORPORATION, OF NEW YORK, N. Y., A CORPORATION OF VIRGINIA.

VENETIAN BLIND.

Application filed July 7, 1925. Serial No. 41,944.

This invention relates to Venetian blinds.

One object of the present invention is to improve the construction and mode of operation of the devices for tilting the slats of 5 Venetian blinds into different positions and for holding the slats in adjusted positions against wind pressure and other disturbing forces.

Another object of the invention is to improve 10 the construction of the devices for supporting a Venetian blind in operative position with a view of facilitating the setting up of the blind and the dismounting of the same.

Other objects of the invention are to improve 15 the construction and arrangement of various other parts of Venetian blinds.

With these and other objects in view, the invention comprises the novel and improved 20 features, constructions, and combinations of parts hereinafter described and particularly pointed out in the claims, the advantages of which will be readily understood and appreciated by those skilled in the art.

The invention will be clearly understood 25 from the accompanying drawings, illustrating the invention in its preferred form, and the following detailed description of the constructions therein shown.

30 In the drawings

Fig. 1 is a view in front elevation of a Venetian blind embodying the invention;

Fig. 2 is a plan view of the construction 35 illustrated in Fig. 1;

Fig. 3 is a detail view in side elevation illustrating certain devices for supporting the blind shown in Fig. 1;

Fig. 4 is a view in horizontal section taken 40 substantially on the line 4—4 of Fig. 1;

Fig. 5 is a view similar to Fig. 3, showing a modified construction;

Fig. 6 is a plan view of the construction 45 shown in Fig. 5;

Fig. 7 is a view in vertical section taken substantially on the line 7—7 of Fig. 1;

Fig. 8 is a view in vertical section taken 50 substantially on the line 8—8 of Fig. 1;

Fig. 9 is a view similar to Fig. 8 showing certain of the parts in different positions;

Fig. 10 is a plan view illustrating certain 55 of the parts shown in Fig. 7;

Fig. 11 is a view in vertical section taken substantially on the line 11—11 of Fig. 1;

Fig. 12 is a view in vertical section taken substantially on the line 12—12 of Fig. 11; 55 and

Fig. 13 is a view in horizontal section taken substantially on the line 13—13 of Fig. 12.

In the form of the invention illustrated 60 in the drawings of this application, the blind comprises a series of slats, indicated at 2, suspended from a tilting bar, indicated at 4, which is tiltingly supported upon a supporting bar, indicated at 6. In order to facilitate the setting up and dismounting of the blind, the ends of the supporting bar 6 are 65 removably mounted on and secured to end brackets 8 and 10, adapted to be secured to the sides of a window frame. Each of these 70 brackets is provided with a substantially horizontal plate or shelf 12, upon which an end of the supporting bar rests, and the supporting bar is secured to the bracket by means of a screw 14 or other suitable fastening device passing through a slot 15 in the shelf 12 from the under side of the shelf and driven into the supporting bar, this slot 75 preferably having an open end as shown in Fig. 4. To hold the supporting bar securely 80 in place on the shelf, the shelf is provided adjacent its forward side with an elevation 16 arranged to engage the forward part of the head of the fastening device 14 when the fastening device is driven home. This 85 will prevent the fastening device from being disengaged from the slot 15 by a forward movement of the supporting bar with relation to the bracket. The supporting bar, however, may be readily removed from the 90 brackets 8 and 10 upon partially withdrawing the fastening devices 14.

In the present construction the tilting bar 4 is pivotally supported from the supporting bar 6 by means of brackets 18 and 20, secured to the supporting bar, and each provided with a downwardly extending arm in which is formed a bearing for one of the pivot studs 22 attached to plates 23 and projecting from the ends of the tilting bar. 100 The slats 2 are suspended from the tilting bar by means of tapes 24 attached at their upper ends to the tilting bar in the manner shown in Fig. 8.

The pivots for the tilting bar are located 105 with relation to the bar, so that the bar is

arranged to swing about an axis below its center of gravity in order that the weight of the bar, when tilted into position to close the slats, will tend to maintain the slats in closed positions. As shown in Fig. 7, the tilting bar is substantially rectangular in cross section, and is pivoted to swing about an axis located nearer to one of its wider sides than the other.

10 The tilting bar is arranged to be tilted into different positions preferably by means of cords 28 and 30, extending in opposite directions about the bar and each secured at its end to the bar, as shown in Fig. 7. The 15 cord 28 extends from the tilting bar directly downwardly. The cord 30, however, extends from the bar upwardly over a pulley 32, rotatably mounted upon the bracket 18. Thus the tilting bar may be tilted in opposite directions by pulling downwardly on the respective cords 28 and 30.

15 In the present form of the invention the tilting bar is provided with a frictionally acting brake mechanism for holding the bar in any position in which it is tilted. This 20 mechanism comprises preferably a brake segment 34, attached to one end of the tilting bar, and a brake shoe 36 mounted on one end of a spring arm 38 secured to the supporting bar 6. The brake segment 34 is provided with a peripheral V-shaped recess 35, and the brake shoe 36 is also V-shaped to fit into the recess 35. This construction provides a highly efficient braking action between the brake segment and the brake shoe, and enables the tilting bar to be held by the brake mechanism in any position in which it is tilted.

25 As shown clearly in Fig. 8, the upper part 30 of the spring arm or plate 38 has an angular formation and bears upon the bracket 18 at the apex of this angle so that it may be rocked about its bearing. The spring plate is secured to the supporting bar by means 35 of screws 39 and 41 or other suitable fastening devices, of which the screw 39 passes through the plate at its bearing point and the screw 41 passes through the plate adjacent the end thereof remote from the brake- 40 shoe. Thus the pressure of the brakeshoe on the brake segment 34 may be readily adjusted by adjusting the screw 41.

45 The brake segment 34 is preferably located so that the central part of the braking surface of said segment is somewhat farther from the axes of the tilting bar than the ends of the braking surface of the said segment. This result may be secured by locating the pivots 22 and the brake segment so 50 that the center of the brake segment is somewhat above the axial line of said pivots, as shown in Fig. 8. The brake segment is arranged in the manner described with relation to the axis of the tilting bar so that 55 the brake shoe will press with less force upon

the braking surface of the brake segment when the tilting bar has been tilted to its limiting position in either direction from a horizontal position. With the tilting bar in either of its limiting tilted positions, the 70 leverage produced when either of the cords 28 or 30 is pulled downwardly to tilt the bar toward a horizontal, will be less than when the bar is in any other position. This 75 low degree of leverage, however, will be compensated for by the relatively light pressure of the brake shoe on the braking surface of the brake segment so that the tilting bar may be readily tilted.

75 The bracket 18 is preferably constructed so to locate the pulley 32 in spaced relation to the brake segment 34 so that there will be no liability that the cord 30 will engage the periphery of the brake segment and jam between the same and the brake shoe, or that 80 said cord will become engaged between the brake segment and the adjacent arm of bracket 18. Also the cord 28 preferably is located inside of the cord 30 to prevent the cord 28 from engaging the periphery of the 85 brake segment.

85 The tilting bar 40 is supported at its ends only by the brackets 18 and 20 and the entire 90 weight of the slats of the blind is carried by this bar. In order to prevent the central portion of the bar from sagging, the bar is provided with a link 40 for supporting the central portion on the bar. This link is 95 itself supported and is connected with the bar in such a manner as to allow the bar 100 to tilt substantially through an angle of 180°. As shown in the drawing, the link 40 is pivotally connected with the tilting bar by means of a transverse bar or head 41 engaging in a recess 42 in the tilting bar, and the body of the link engages in a slot 43 in the tilting bar leading to the recess 40 and having the angular form shown clearly in Fig. 11 of the drawing. The slot 105 43 is preferably shaped so that the link 40 may turn with relation to the tilting bar through an angle of somewhat over 90°. The upper end of the link 40 is supported upon a guide rod 44 secured to the supporting bar 6. This guide rod enables the link 110 110 to tilt with the tilting bar when the tilting bar has reached its limiting position with relation to the link 40 by reason of the engagement of one end of the slot 43 with the link. The guide 44 is preferably curved 115 in an arc struck about the axis of the rod 40 as a center. Through the combined angular movement of the tilting bar with relation to the link 40 and the swinging of the link allowed by the sliding movement of the 120 link along the guide 44, the tilting bar is 125 enabled to tilt through an angle of substantially 180°.

130 The slats are arranged to be raised and lowered by means of cords 46, each con-

nected at one end with the lowermost slat and extending upwardly through slots in the other slats. These cords pass over pulleys 48 mounted in slots in the supporting bar, and both pass together over a pulley 50 mounted in a slot at one end of the supporting bar, the cords extending downwardly from the latter pulley and preferably being secured together after leaving this pulley. The right-hand bracket 10 which carries the supporting bar, is provided with a slot 52 having an open end to receive the portions of the cords 46 extending downwardly beyond the pulley 50. This slot greatly facilitates the setting up of the blind, since, when the supporting bar with the parts of the blind suspended therefrom, is placed on the brackets 8 and 10, the cords will readily assume their proper location within the slot. The brackets 8 and 10 are each provided with a portion 54, as shown in Fig. 3, overhanging the supporting bar at the rear thereof so as to prevent the supporting bar from tilting.

In the modified construction shown in Figs. 5 and 6, the bracket 8, is formed with an upwardly extending portion or projection 56 in which is formed a slot 58 to receive a fastening device 60 to pass through the slot and driven into the supporting bar. In this construction the head of the fastening device 60 engages in a depression in the projection 56 when the fastening device is driven home, so that a fastening device cannot then be disengaged from a slot by an upward movement of the forward part of the tilting bar. Upon loosening the fastening device to disengage the head thereof from the depressed portion of the projection 56, the forward part of the supporting bar may be lifted to disengage the fastening device from the slot.

It is to be understood that the invention is not limited to the particular construction of the illustrated embodiment of the invention, but that the invention may be embodied in other forms within the scope of the claims.

What is claimed as new is—

1. A Venetian blind construction comprising a supporting bar, a bracket for the supporting bar provided with a plate having a slot with an open end in one part thereof, slats suspended from the supporting bar, a fastening device having a shank adapted to be passed through the slot and driven into the bar and a head, and an elevation on the plate arranged to engage said head to prevent the withdrawal of the fastening device by a relative movement of the bar and bracket in the direction of the plane of said part of the plate.

2. A Venetian blind comprising a supporting bar, a side bracket for the supporting bar formed with a slot, slats suspended

from the supporting bar, a fastening device inserted in the slot and driven into the bar and having a head, and a projection on the bracket for engaging the head to prevent the fastening device from being disengaged from the slot except when said device is partially withdrawn from the bar.

3. A Venetian blind comprising a tilting bar, slats connected with the tilting bar, a sag-preventing link pivoted to the tilting bar at one end, and means for supporting the other end of the link to allow the link to swing with the tilting bar during a portion of the movement of the bar.

4. A Venetian blind comprising a tilting bar, slats connected with the tilting bar, a sag-preventing link pivotally connected at one end with the tilting bar, a bearing for the other end of the link along which the link is arranged to slide, said bearing being curved about the point of pivotal connection of the link with the bar as a center.

5. A Venetian blind comprising a tilting bar, slats connected with the tilting bar, a sag-preventing link pivotally connected at one end with the bar, and means for slidably supporting the other end of the link to allow the link to swing with the tilting bar as the bar is tilted.

6. A Venetian blind comprising a supporting bar, side brackets for removably holding the supporting bar, one of which brackets is formed with a portion overhanging the supporting bar to prevent tilting of said bar and means spaced from said overhanging portion for securing the bar against being lifted from the bracket.

7. A Venetian blind comprising a supporting bar, slats suspended from the supporting bar, pulleys mounted on the supporting bar, cords for raising and lowering the slats passing over said pulleys, and side brackets for removably supporting the ends of the supporting bar, one of which brackets is provided with an open ended slot to receive the downwardly extending portions of said cords.

8. A Venetian blind comprising a tilting bar, slats suspended from the tilting bar, cords for actuating the tilting bar, a brake for the tilting bar, a pulley above the tilting bar for guiding one of said cords, and means for supporting the pulley in spaced relation to the brake to prevent the jamming of the latter cord in said brake.

9. A Venetian blind comprising a tilting bar, a brake for the tilting bar, slats suspended from the tilting bar, a cord for tilting the bar in one direction, a pulley above the bar for guiding said cord, and a cord for tilting the bar in the opposite direction extending downwardly past an upwardly extending portion of the first cord on the side of the latter cord opposite the brake.

10. A Venetian blind comprising a sup-

porting bar having a longitudinal slot extending through one end of said bar, pulleys mounted in a slot in said bar, one of which pulleys is located at the latter end 5 of said bar, a bracket having a plate on which the latter end of the supporting bar is removably held, said plate being formed with a slot registering with the slot in the said bar and lifting cords for the blind extending over said pulleys and downwardly 10 through the slot in said plate.

11. A Venetian blind comprising a tilting bar, slats connected with the tilting bar, means for pivotally supporting the tilting 15 bar, one or more cords connected with the tilting bar for tilting the same, a brake shoe, and a brake member mounted on the tilting bar, engaged by said brake shoe and having its surface eccentric to the arc of 20 rotation of the tilting bar so that the braking effect will vary with the leverage produced upon pulling the tilting cords when the bar is in different positions.

12. A Venetian blind comprising a supporting bar, a bracket for holding the supporting bar having a plate upon which said bar rests, and a slot with an open end in a part thereof adjacent one side margin of 30 the bar and a portion overhanging the opposite side margin of the bar to prevent tilting of said bar, and a fastening device engaging in the slot for removably holding the bar in position on the bracket.

13. A Venetian blind comprising a tilting 35 bar, slats connected with the tilting bar, means for pivotally supporting the tilting bar, cords connected with the tilting bar for tilting the same, and a brake for the tilting bar for holding the same in position, arranged to vary the braking effect to 40 compensate for the variations in leverage pro-

duced upon pulling the tilting cords with the bar in different positions.

14. A Venetian blind comprising a tilting bar, means for pivotally supporting the tilting bar, slats suspended from the tilting bar, a tilting cord attached to the bar and extending beneath the same, a pulley arranged forwardly of and above the bar over which the said cord passes, and a second cord attached to the bar and extending forwardly 50 over the same and then directly downwardly.

15. A Venetian blind comprising a tilting bar, means for pivotally supporting the tilting bar below its center of gravity, slats suspended from the tilting bar, a tilting cord attached to the bar and extending beneath the same forwardly, a pulley arranged above and forwardly of the bar over which said 60 cord passes, and a second cord attached to the bar and extending forwardly over the same and then directly downwardly.

16. A Venetian blind comprising in combination a tilting bar, a series of parallel slats, connections between the slats and the tilting bar for causing the slats to turn with said bar, and a brake for holding the tilting bar in position, arranged for adjustment to regulate the frictional action of the brake. 65

17. A Venetian blind comprising in combination a tilting bar, a series of parallel slats, connections between the slats and the tilting bar for causing the slats to turn with said bar, a brake segment attached to the 75 tilting bar, and a relatively fixed brake shoe for engaging said segment, arranged for adjustment to regulate the pressure of the brake shoe on said segment.

Signed at New York, N. Y., this 6th day of July, 1925.

WALTER E. DUNCANSON.
